(57) **CLAIM**

The ornamental design for a portable gas stove, as shown and described.

DESCRIPTION

1. Portable gas stove

1.1 : Perspective

1.2 : Front

1.3 : Back

1.4 : Left

1.5 : Right

1.6 : Top

1.7 : Bottom

1.8 : State in use

The broken lines showing portions of the portable gas stove form no part of the claimed design.

The present design relates to a portable gas stove that maintains temperature of a container containing food or is used as cookware.
